J. Y. ROBERTSON

CASTER

Original Filed April 18, 1922

FIG. 1 FIG. 2

FIG. 3 FIG. 4

INVENTOR.

J. Y. Robertson
BY

C. C. Hines ATTORNEY

UNITED STATES PATENT OFFICE.

JOHN Y. ROBERTSON, OF EL PASO, TEXAS.

CASTER.

Original application filed April 18, 1922, Serial No. 554,807. Divided and this application filed January 7, 1924. Serial No. 634,822.

To all whom it may concern:

Be it known that I, JOHN Y. ROBERTSON, a citizen of the United States, residing at El Paso, in the county of El Paso and State 5 of Texas, have invented new and useful Improvements in Casters, of which the following is a specification.

This invention relates generally to casters, and the present application is a division of 0 my prior application, Serial No. 554,807, filed April 18, 1922. The primary object of the present invention is to provide a caster which shall be of simple construction, strong and durable, and reliable and 5 efficient in use.

A further object of the present invention is to provide a caster which is assembled in such manner that the parts thereof, while permitting free movement at all times, can 20 not become disordered or deranged and which are properly maintained within the supporting ferrule.

With these and other objects in view, the invention consists of the features of 25 construction, combination and arrangement of parts, hereinafter fully described and claimed, reference being had to the accompanying drawing, in which:—

Figure 1 is a sectional view taken through 30 a caster constructed in accordance with the invention,

Figure 2 is a transverse sectional view taken on line 2—2 of Figure 1,

Figure 3 is a top plan view of the caster, 35 and

Figure 4 is a fragmentary perspective view of the caster barrel.

It is to be understood that the claims of 40 the present application are directed to the caster construction per se, while the claims of application No. 554,807 are directed to a caster embodying a novel type of insect guard.

Referring now more particularly to the 45 drawing, 5 represents a ferrule or body to be fitted to the leg of the furniture to be equipped therewith, and this ferrule may be polygonal in cross-section, circular or oval to correspond with the shape of the leg to which it is to be applied. This ferrule may be formed of any suitable material, and may 50 be either enclosed in a channel or opening

bored in the furniture leg or may be secured at its upper end to the lower end of such leg. In the latter instance, the leg will fit 55 between the upstanding ears 6 at the upper end of ferrule 5, and a bolt or pin may be passed through the openings 7 in the said ears to firmly secure the parts together.

The ferrule 5 is provided with a centrally 60 or axially disposed recess or cavity opening in from the lower end thereof and being substantially coextensive with the said ferrule. This recess snugly accommodates an outer barrel indicated at 8, and this outer 65 barrel has nested therein an inner barrel or sleeve 9. The sleeve or inner barrel is of less length than the outer barrel, and engages at its upper end with a shoulder 10 formed in the inner circumference of the 70 said outer barrel. The sleeve 9 at its lower end carries an annulus 11 disposed at right angles to the said sleeve. In the use of the device as an insect-proof caster, there will be formed integral with this annulus, 75 at the outer extremities of the latter, a cup 12. The cup 12 lies almost entirely below the plane of the annulus 11 and is formed by bending the metal of which the annulus is formed downwardly and in substantially 80 circular shape in cross-section and upwardly so that the outer edge of the said metal terminates in a plane substantially even with the plane of the said annulus. The free edge of cup 12 is spaced from the 85 outer edge of the annulus a distance sufficient to enable an insecticide in the form of a powder or liquid to be introduced to the cup and held thereby, and this gap causes any vermin upon the exterior of the 90 cup to enter the latter in an attempt to obtain a footing or hold upon either the annulus or the ferrule 5. This insect cup or guard feature constitutes the subject-matter of my original application filed April 95 18, 1922, Serial No. 554,807.

The caster includes the wheel supporting bracket 13 carrying a wheel 14 formed of any suitable material and mounted in any suitable manner, and a stem 15 projects upwardly from this bracket and fits snugly within the nested ferrules 8 and 9. The stem protrudes at its upper end above the upper extremity of ferrule 8 and is pro-

vided with a transverse opening to receive a cotter pin or other securing element indicated at 16, this pin confining a washer 17 between itself and the adjacent end of the ferrule 8.

A disk 18 is carried by the upper end of bracket 13 and rests upon the latter, and is provided on its upper surface and near its outer edge with an annular groove to receive the anti-friction balls 19, while the under surface of the annulus 11 directly overlying the groove of the disk is similarly grooved, the grooves of the disk and annulus constituting between them a recess for the balls 19.

By constructing the device in this manner it is apparent that the several parts of which the caster is formed will be securely held together and maintained against disorganization. After the outer and inner ferrules or sleeves 8—9 are properly assembled the stem of the caster is inserted through the lower end of the sleeve 9, the balls 19 having previously been properly positioned upon the disk 18 and in the groove thereof. After the washer and cotter pins 17—16 have been properly applied to the upper end of the stem, these parts of the device will be firmly secured together, yet the caster bracket is at all times free for relative movement. By extending the inner ferrule of sleeve 9 upwardly in the manner indicated, danger of the insecticide or vermin repellent gaining access to the interior of the caster is entirely obviated. The annular cup which contains this fluid or powder is so located that vermin in crawling up the caster must enter the cup in order to obtain a footing or hold upon that part of the caster construction which is directly connected with the leg of the furniture. Furthermore, it will be noted that the container or cup is so shaped and constructed as to offer little or no obstruction and not to detract from the appearance of the furniture to which the improved caster is applied.

In the present instance a caster and bracket of conventional type is shown; however, it will be understood that the inventive characteristics may with facility be carried out in connection with caster structures of various shapes, forms, sizes and types, and while the above is a description of the invention in its preferred embodiment, it will be understood that various changes in the minor details of construction and arrangement of parts may be made,

without departing from the spirit of the invention as defined by the claims.

Having thus fully described my invention, I claim:

1. In a device of the class described, a ferrule, a barrel arranged within said ferrule, the said barrel being of larger diameter near its lower end and providing a shoulder at the juncture of the larger with the smaller diameters, a sleeve fitting in the larger diameter of said barrel and engaging said shoulder, an annulus at the lower end of said sleeve, a stem extending through said sleeve and barrel and secured therein, a disk held by said stem, and anti-friction balls interposed between said disk and said annulus.

2. In a device of the class described, a ferrule having a recess therein, a barrel disposed within and substantially coextensive with said recess, the said barrel being of enlarged diameter near its lower end, a shoulder at the juncture of the larger and smaller diameters of said barrel, a sleeve fitting within the larger bore of said barrel and abutting said shoulder, an annulus at the outer end of said sleeve, a caster stem entering said sleeve and passing entirely through said barrel, a disk carried by said stem and lying below said annulus, cooperating grooves on said annulus and disk providing a ball recess, anti-friction balls in said recess, and a cotter pin maintaining said stem assembled within said barrel.

3. In a device of the class described, a barrel having its bore enlarged from the middle portion thereof on to an end and the walls of said enlarged portion diverging toward the extremity of the barrel, a shoulder at the juncture of the enlarged with the smaller portions of the bore, a sleeve in said barrel having its inner end engaged with said shoulder and of the same diameter as the smaller portion of said bore, the said sleeve flared toward its outer end and lying snugly against the walls of said larger bore, a caster stem extending through the nested sleeve and barrel, means for securing said stem therein, and anti-friction members interposed between said caster and the lower portion of said sleeve.

In testimony whereof I affix my signature in presence of two witnesses.

JOHN Y. ROBERTSON.

Witnesses:

B. C. ANTHONY,
CONSTANCE O. ANTHONY.
